UNITED STATES PATENT OFFICE.

WALTER S. BROWER AND EDMUND CONKLIN, OF ALBANY, NEW YORK;
SAID CONKLIN ASSIGNOR TO SAID BROWER.

MUSTACHE-GUARD.

SPECIFICATION forming part of Letters Patent No. 357,571, dated February 15, 1887.

Application filed June 5, 1886. Serial No. 204,204. (No model.)

To all whom it may concern:

Be it known that we, WALTER S. BROWER and EDMUND CONKLIN, both citizens of the United States, residing at Albany, in the county of Albany and State of New York, have invented a new and useful Mustache-Guard, of which the following is a specification.

Our invention relates to a detachable mustache-guard which is readily attachable to a cup or other drinking-vessel having correspondence of size with this guard, and detachable therefrom and portable on the person of the user; and it consists of the combination of devices and elements, hereinafter particularly described, and set forth in the claims.

The objects of our invention are to provide a detachable mustache-guard which can be readily applied to drinking cups, glasses, and other drinking-vessels and be securely connected with the same at will, and when not used to be readily detachable and portable without inconvenience to the user in carrying the same. We attain these objects by the means illustrated in the accompanying drawings, forming a part of this specification, in which—

Figure 1 is a perspective view of our new and improved mustache-guard when detached from the drinking-vessel. Fig. 2 is a perspective view of a drinking-vessel having our mustache-guard applied thereto.

The same letters refer to the same parts in the several views.

Our mustache-guard is composed of the guard-plate A, horizontal keeper B, and elastic holding-piece C.

The guard-plate A is made of any suitable material, and preferably of sheet metal, such as tin, silvered or nickle-plated brass, or equivalent metal having cleanly surfaces. The outer edges, *a a*, of this guard are made with forms which will correspond with that of the drinking-vessel at its rim-edge, and these edges *a* are preferably curved downwardly to a short distance to produce on the lower side a slight concave seat, *s*, as shown. Made with this guard-plate, at two points on the edges *a a*, are the holding-lips *a' a'*, for engagement with the side wall of the vessel, to hold the

guard from shifting rearward. These holding-lips can be made in connection with the guard-plate or be secured thereto by solder, rivets, or any other well-known means, and are made to project to a short distance below the plane of the lower side of said plate. Made in the front side portion of this plate, and between edge sections *a a*, is the concave-form recess A, which is made ordinarily about one and one-half inch in length, and with a depth of about five-eighths to three-quarters of an inch from the line of curvature of edges *a a*. The rear side edge of this guard-plate A is also made with a concave-form recess, A', the edge of which at the middle of length of the plate approaches the edge of recess A' to within about one-half of an inch.

The keeper B is preferably made of stiff wire bent in circular form, and has its ends connected with guard-plate A by solder or rivets, or any other well-known means practiced by the trade. This circular form of the keeper is preferred, though the portions of the wire composing the keeper can be made to run in angular lines from the plate A to the point *x* of intersection of the two branches of the wire, as indicated by dotted lines in Fig. 1. At the point of intersection of the two branches *b b* of this keeper there is provided an elastic holding-piece, C, made preferably in connection with the keeper B by twisting the wire of the two branches *b b* together from the point of their intersection, as shown, so as to furnish a sufficient length of material for bending rearwardly and downwardly to a sufficient distance to give the holding-piece a bearing on the rear side of the vessel at a distance below the rim of the same. The drawings show that this holding-piece is made to be in form to include a convenient handle, C', yet this is not essential, as this upwardly-projecting handle can be dispensed with and the holding-piece be made to extend first horizontally rearwardly, and then downwardly; yet in most cases we would prefer to retain this handle-form of holding-piece, as it serves as a convenient means for placing and removing this mustache-guard from the vessel.

When this device is properly placed on the drinking-vessel D, the concavities *s* of edges *a*

will receive the rim-edge of the vessel, and the holding-lips $a' a'$ will engage with the outside of the wall in front of the vessel at two points and react against the elastic holding-piece C, which will have bearing against the wall of the vessel on its rear side, and these devices—the lips $a' a'$ and holding-piece C—will hold the guard from shifting in any direction on the rim of the vessel, while the keeper B will hold the guard-plate horizontal and suitably connected with the reacting elastic holding-piece C. The concave line of edge, which is produced by recess A', operates with the rim of the vessel in front to produce (when this guard is in place on the vessel) a suitable opening through which a person can drink from the vessel. The recess A', formed by the concave form of rear side edge of the guard-plate, operates to permit the drinker's nose to pass down into the upper end of the vessel.

This mustache-guard can be made in several sizes to fit the several sizes of rims of drinking-vessels, and is intended to be for the use of individuals when traveling or away from home.

Having described our invention, what we claim, and desire to secure by Letters Patent, is—

1. In a detachable mustache-guard, the combination, with the guard-plate A, provided with a recess in its front side edge and holding-lips connected with the rim-edge sections, $a a'$, of the reacting holding-piece C, and a con-

necting-piece between said guard-plate and holding-piece, substantially as and for the purpose set forth. 35

2. In a detachable mustache-guard, the combination, with guard-plate A, made with edge-sections for seating on the rim of a drinking-vessel, and recess A' in its front side edge 40 and provided with holding-lips $a' a'$ for engagement with the front side wall of the vessel, of the elastic holding-piece C, and a connecting-piece between said holding-piece and said guard-plate, substantially as and for the 45 purposes set forth.

3. In a detachable mustache-guard, the combination, with guard-plate A, having concave recess A' and edge sections, $a a'$, provided with seats $s s$, and holding-lips $a' a'$, of the reacting 50 holding-piece C, handle C', and keeper B, connecting said handle and holding-piece with said guard-plate, substantially as and for the purposes set forth.

4. The combination, with a drinking-vessel, 55 of a detachable mustache-guard which is formed by the combination of the guard-plate A, provided with recess A', edge seats, $a s$, and holding-lips a' , and the elastic holding-piece C and keeper B, all substantially as and for the purposes set forth.
